His Attorney.

UNITED STATES PATENT OFFICE

ARTHUR G. ZIMMERMAN, OF SCHENECTADY, NEW YORK, ASSIGNOR TO GENERAL ELECTRIC COMPANY, A CORPORATION OF NEW YORK

SPEECH-CURRENT APPARATUS

Application filed February 14, 1928. Serial No. 254,296.

My invention relates to speech current generators and motors, and has for its principal object the provision of an improved apparatus which may be efficiently operated either to convert speech current into sound or to generate electric current which is dependent on sound.

Various types of speech current apparatus have been provided in the past. Many of these apparatus include a coil which is mounted on a diaphragm and is arranged to move in a magnetic field either in response to speech current supplied to the coil or in response to sound impulses applied to the diaphragm.

As pointed out in Patent No. 1,707,570, issued April 2, 1929, to Chester W. Rice, and assigned to the same assignee as the present application, the operating efficiency of such apparatus may be improved by the provision of conductive rings of copper or similar low resistance materials embedded in the pole pieces of the magnet through which the magnetic field surrounding the movable coil is produced. With this construction, the conductive rings embedded in the pole pieces form low resistance secondary circuits which reduce the reactive component of the diaphragm-coil impedance and increase the operating efficiency of the apparatus. In accordance with my invention, this efficiency is further increased by making the conductive rings in the form of layers of conductive material which are rolled, electroplated or otherwise placed on the active surfaces of the pole pieces. This arrangement of the conductive rings has the important advantage that it permits very close coupling between these rings and the movable diaphragm coil, thus greatly decreasing the inductance of the movable coil.

My invention will be better understood from the following description when considered in connection with the accompanying drawings and its scope will be pointed out in the appended claims.

Referring to the drawings, Fig. 1 is a sectional view of a speech current apparatus wherein my invention has been embodied,

and Figs. 2 and 3 illustrate various details of the pole pieces of this apparatus.

This apparatus includes a coil 4 which is mounted on a diaphragm 5 and is arranged to move between the pole pieces 6 and 7 of a magnet shown as provided with a field or exciting coil 8. As shown more clearly in Figs. 2 and 3, the pole piece 6 is provided with a copper lining 9 and the pole piece 7 is provided with a copper covering 10.

It will be readily understood that the conductive coverings 9 and 10 may be made very thin and may extend somewhat beyond the active areas of the pole pieces so that the flux of the magnet is highly concentrated in the path of the moving diaphragm coil 4. Under these conditions, the apparatus has been found to operate very efficiently when utilized to convert speech current into sound or vice versa. While both the pole pieces have been shown as provided with a conductive covering, it should be understood that similar results may be secured by increasing the thickness of one of the coatings and omitting the other coating.

What I claim as new and desire to secure by Letters Patent of the United States is:

1. A speech current apparatus including a pair of magnetic pole pieces, layers of conductive material arranged to cover the active areas of both of said pole pieces, a diaphragm, and a coil mounted on said diaphragm and arranged to move between said layers of conductive material.

2. A speech current apparatus including a pair of magnetic pole pieces, layers of non-magnetic conductive material arranged to cover the active areas of both of said pole pieces, a diaphragm, and a coil mounted on said diaphragm and arranged to move between said layers of non-magnetic conductive material.

3. A speech current apparatus including a pair of magnetic pole pieces, layers of copper arranged to cover the active areas of both of said pole pieces, a diaphragm, and a coil mounted on said diaphragm and arranged to move between said layers of copper.

4. A speech current apparatus including a pair of magnetic pole pieces, the active area

of one of said pole pieces being electro-plated whereby it is covered with a thin layer of conductive material, a diaphragm, and a coil mounted on said diaphragm and arranged to move between said pole pieces.

5 In witness whereof, I have hereunto set my hand this 13th day of February, 1928.

ARTHUR G. ZIMMERMAN.
